(57) **CLAIM**

The ornamental design for a forward chassis fairing, as shown and described.

DESCRIPTION

FIG. 1 is a perspective view of a forward chassis fairing according to our new design;

FIG. 2 is a top view of the forward chassis fairing of FIG. 1; and,

FIG. 3 is a front view of the forward chassis fairing of FIG. 1. The rear of the forward chassis fairing is unornamented. The broken lines shown in FIGS. 1-3 form no part of the claimed design.

FIGS. 1-3 illustrate a first embodiment of our novel design suitable for use on the left side of a vehicle. Our novel design also includes a second embodiment suitable for use on the right side of a vehicle, which is mirror symmetrical to FIGS. 1-3 and therefore not separately illustrated.

1 Claim, 3 Drawing Sheets
